United States Patent

Des. 234,618
Patented Mar. 25, 1975

234,618

TOP LAUNCHER OR SIMILAR ARTICLE

John R. Hedger, 4958 E. Carmen,
Fresno, Calif. 93727

Filed Aug. 16, 1973, Ser. No. 388,821

Term of patent 14 years

Int. Cl. D21—01
U.S. Cl. D34—15 AH

FIG. 1 is a front perspective view of a top launcher or similar article showing my new design;

FIG. 2 is a top plan view thereof, the side opposite being substantially identical;

FIG. 3 is a right side elevational view thereof, the side opposite being substantially identical;

FIG. 4 is a front end elevational view thereof; and,

FIG. 5 is a back end elevational view thereof.

I claim:

The ornamental design for a top launcher or similar article, substantially as shown and described.
